UNITED STATES PATENT OFFICE.

DAVID I. KELLY, OF NEW YORK, N. Y.

SIGNAL.

1,075,109.

Specification of Letters Patent. Patented Oct. 7, 1913.

Application filed January 28, 1913. Serial No. 744,714.

To all whom it may concern:

Be it known that I, DAVID I. KELLY, a citizen of the United States, residing at New York city, in the county of New York and State of New York, have invented new and useful Improvements in Signals, of which the following is a specification.

The general object of the invention is to have the approaching of a railroad train to a danger signal or the passing of the train beyond such signal, and the approaching of the train to a grade crossing, indicated by a signal. And to these ends the invention resides first, in providing a car with whistle operating means and a track with means for controlling the operation of the whistle operating means and arranging these parts so as to coact and effect the opening of the whistle valve when the car is at a predetermined place on the track; and second, in providing means for effecting the locking of the whistle operating means upon coaction with the controlling means.

Other objects will appear and be better understood from that embodiment of my invention of which the following is a specification, reference being had to the accompanying drawings forming part hereof, in which:

33. Figure 1 is a side elevation of a railway locomotive equipped with one embodiment of my invention. Fig. 2 is a view looking at right angles to Fig. 1 showing the greater portion of the whistle operating means and controlling means and a sufficient portion of a locomotive to illustrate the application of the whistle controlling means thereto. Fig. 3 is a detail side elevation showing the position of the controlling means and whistle operating means when coacting to sound the whistle for a grade crossing. Fig. 4 is a detail horizontal section of the casing. Fig. 5 is a detail side elevation showing by dotted lines the position of the means for effecting the locking of the signal operating means. Fig. 6 is a vertical cross section on the line 6-6 of Fig. 5 and showing the controlling means in inoperative position. Fig. 7 is a view similar to Fig. 6 but showing the controlling means in operative position. Fig. 8 is a contracted diagrammatic view showing the arrangement of the controllers for effecting the sounding of the whistle upon approaching a grade crossing and the locking of the whistle upon the train's passing a danger signal.

In the embodiment shown in the drawings *a* indicates the whistle of the locomotive, *b*—*b* the driving wheels, *c* one of the driving wheel trucks, *d* the track, *e* a semaphore signal, and *f* an operating lever.

In carrying out my invention I attach one end of a flexible element 5 such as a cable, to the valve rod 6 of the whistle *a*. This flexible element 5 is then directed through an open-ended casing or tube 7 carried by the boiler of the locomotive 8 and has its lower end connected to one end of a lever 9 whose fulcrum 10 is suitably connected to the truck *c*. The other end of the lever is connected to the truck by a retractile spring 11 which operates to hold the lever 9 horizontally or substantially so, in which position the flexible element 5 will be relaxed so as to exert little or no pull on the whistle valve rod 6.

Connected to the lever 9 and preferably at a point between the fulcrum 10 and spring 11, is the upper end of a rod 12. By preference this rod is T-shaped in cross section and is directed through a correspondingly shaped guide 13 located in a box or casing 14 which is suitably connected to the truck *c*. The said box having openings in opposite walls to admit of the passing therethrough of the rod 12 whose lower end extends to a point below the truck *c* and carries a shoe 15.

The casing 14 is provided with a door 16 which when closed, may be locked with a key actuated lock 17.

A gravity latch 18 located in the casing has one end directed into the path of movement of a stud 19 carried by the rod 12 and directed through a slot in one side wall of the guide 13. When the rod 12 is in its normal position the stud 19 is disposed below the latch 18 but upon the rod moving upwardly beyond a predetermined point the stud effects the lifting of the free end of the latch until the latter is moved beyond the plane of movement of the stud, at which time the latch gravitates to normal position so as to intercept the rod by contacting with the stud and thereby prevent return movement of the rod.

Arranged between the rails of the track *d* are the controllers 20 and 21 for the whistle operating means above described. The controllers 20 may be of any preferred construction as that shown in Figs. 2 and 3 where it will be seen that the middle portion of the upper surface of the controller

2
is a trifle above the plane of the track rails 22-22. The controller 21 includes a section of rail *g* arranged so as to correspond in height or approximately so to the track 5 rails 22, and a trip plate *h* carrying pins 23 which are connected to pins 24 carried by the rail section *g*, by means of links 25. A plurality of connecting rods 26-26 connected together by bell cranks 27-27 connect 10 the trip plate *h* with the rod 28 which connects the operating lever *f* with the semaphore *e* and an additional connection in the form of a bell crank 29 and a rod 30 is established between the semaphore and the 15 rod 28.

The controllers 20 are arranged so as to effect the sounding of the whistle when the train is at a predetermined distance from a grade crossing. Referring now to Fig. 8 20 the controllers 20 are arranged in alignment and in spaced relation. Here too, it will be observed that the first two controllers on the right in the said figure are approximately the same in length but longer than 25 the succeeding two. Now with the upper surfaces of these controllers arranged above the plane of the tread surfaces of the track rails 22 and in the path of movement of the shoe 15, it will be manifest that when 30 such shoe contacts with the controllers successively and the parts to which the said shoe is connected, occupy the positions shown in Fig. 2, four blasts of the whistle will be had, the first two of these being relatively long while the second two will be 35 relatively short, this combination of blasts being the usual signal given when a train approaches a grade crossing. It may here be stated that the lifting effect on the rod 40 12 produced by the controllers 20 will not be to a degree sufficient to effect the interlocking of the stud 19 with the latch 18.

Referring now to Figs. 5 to 8 inclusive, it will be seen that the trip plate *h* is arranged 45 so as to operate in unison with the semaphore *e*, the connection being such that when the semaphore is adjusted to indicate a clear track the said trip plate will occupy the position shown in Fig. 6, that is to say, 50 its upper surface will be coincident or substantially so, with the rail section *g* and the

track rails 22, hence it will be out of the path of movement of the shoe 15, but when the semaphore is adjusted to indicate danger as shown in Fig. 8, the upper surface of the said trip plate will be projected considerably beyond the upper surface of the rail section *g* and occupy the position shown in Fig. 7, in which position it will upon the shoe 15 coming in contact therewith, effect the upward movement of the bar 12 until the stud 19 interlocks with the latch 18. Now the whistle will sound even when the shoe is carried beyond the controller 21 and in fact until the latch 18 is disengaged 65 from the stud, which, it will be observed, can be only effected when the train is brought to a standstill and the conductor or other operative in possession of the key, unlocks and opens the door 16 and operates 70 the rod 12 and latch 18 to effect the disengagement of these and permit the rod to move to its normal position.

In arranging the whistle operating mechanism care is given to have the casing 14 75 disposed so that when the door thereof is open its interior will be readily accessible to a person occupying a position at the sides of the wheels.

What is claimed as new is:

In combination with a vehicle having a signal, a vertically movable shoe carried by the vehicle, means operatively connecting the shoe with the signal a member fixed in the path of the vehicle and projecting into 85 the path of the shoe, the shoe being free to return to a normal position after being displaced therefrom by contact with said member, a strip movably mounted on said member, and adapted to be projected beyond the 90 edge thereof into the path of movement of the shoe, means of moving said strip, and a lock mounted upon the vehicle and adapted to retain the shoe in an abnormal position after it has been displaced from its 95 normal position by contact with the strip.

In testimony whereof I affix my signature in presence of two witnesses.

DAVID I. KELLY.
